UNITED STATES PATENT OFFICE

ARTHUR WORRELL, OF ST. JOSEPH, MISSOURI

CHANGE-MAKING MACHINE

Application filed June 5, 1929. Serial No. 368,674.

The present invention relates to improvements in change-making machines, one object of the invention being to provide such a machine with means whereby a predetermined number of coins of small denomination are positioned for ejection in exchange for a single coin of higher denomination, the ejecting device being normally locked and releasable for manual operation by the insertion of a coin of larger denomination.

A further object of this invention is to provide a device of this character which is especially adapted for making change or for vending car tokens, or the like, the construction being simple, durable and inexpensive, and thoroughly efficient and practical in use.

With the foregoing and other objects in view, which will appear as the description proceeds, the invention resides in the combination and arrangements of parts and in the details of construction hereinafter described and claimed, it being understood that changes in the precise embodiment of the invention herein disclosed can be made within the scope of what is claimed without departing from the spirit of the invention.

In the accompanying drawings:—

Figure 1 is a vertical sectional view through one of the coin tubes with the mechanism in normal position, dotted lines illustrating the position assumed by the parts at the final ejection of the coins.

Figure 2 is a view, partly in front elevation and partly in transverse vertical section, showing the parts in normal locked position.

Figure 3 is a sectional view on line 3—3 of Figure 1.

Figure 4 is a section and top plan view of the main lever locking member and a portion of its coin released lever.

Referring to the drawings, the numeral 6 designates a cabinet which is here shown as provided with a removable cover 7 and with a front wall 8, said wall being provided at its upper portion with a transparent window 9 and at its lower portion with a vertical slot 10, the purpose of which will presently appear. The bottom 11 of said cabinet is provided with an outlet opening 12 which is normally covered by a closure 13

longitudinally slidable in guides 15 so as to be slid inwardly to uncover the opening 12 when it is desired to remove the coins therefrom. Such closure 13 is provided with an apertured depending lip 14 which is adapted to cooperate with an apertured projection 16 in the cabinet for the reception of a padlock 17. By these means the closure 13 may be locked in closed position as shown in Figure 1.

Brackets 18 within the cabinet support a coin tube 19 which is open at its upper end so that coins 20 of small denomination may be introduced therein and will fall downwardly to rest upon coin guides 21 at the bottom of the tube, the distance of the guides from the bottom of said tube determining the number of coins to be ejected at each operation, and, as here shown, being five in number. A slidable coin ejector 22 is employed and consists of a plate portion having a forward right-angled end 23 provided with a rearwardly extending apertured lug 24 and a rear upstanding flange 25 which limits the forward ejecting movement of the same to the dotted line position, as shown in Figure 1.

The ejector 22 is horizontally slidable between a pair of guides 26 and 27 supported from one wall of the cabinet.

A modified bell-crank lever 28 has pin-and-slot connection 29 with the lug 24 of the ejecting member 22 and is itself pivotally mounted at 30 to the upper end of a standard 30' mounted upon the bottom of the casing. The opposite end 31 of the bell-crank lever extends through the aforesaid slot 10 so that the same may be manipulated from the exterior of the cabinet, a spring S being employed to normally hold the bell-crank lever in the full line position, as shown in Figure 1, with the ejector 22 in retracted or rearward position and the operating end 31 of said lever elevated.

A guide 32, arranged to receive the ejected coins, has an open tray 33 projecting beyond the face of the cabinet adjacent the free end of the lever arm 31 so as to be readily accessible.

Thus, it will be seen that by depressing

arm 31 of the bell-crank lever 28 so as to cause the same to be moved from the full to the dotted line position, the ejector 22 will eject from guides 21 all of the coins 5 below the lower end of tube 19, the portion 23 engaging the edge of the coins during the movement of the same from left to right, as viewed in Figure 1, while the portion 22 will rest below the lowermost coin adjacent 10 to the lower edge of the tube 19, and thus retain the volume of coins within the tube during this action and until the ejector has assumed the rearward position, at which time the coins which were above those ejected will 15 fall by gravity, the lowermost one resting upon the guides 21 with the proper number of coins positioned for the next operation.

A novel coin-controlled means requires the insertion of a coin 36 (to be changed for a plurality of coins 20) to effect the release and permit manual operation of the lever 28 for a coin-changing operation. To this end, a coin chute 34, having an inlet 35, is disposed at one side of the cabinet. A coin 36, when deposited in said chute, falls by gravity and engages the lower end of an over-balanced lever 37 which slightly initially depresses such lever. This action causes said lever 37, which is pivoted to a support 39 and inclined 20 and arranged at a right angle to catch 40, to laterally swing the free or hooked end 41 of such catch out of the path of movement of said lever 28, and thus permits depressing operation of arm 31 of said lever 28 and ejection of the change or coins 20, the said lever 28 being returned to normal position by the spring S and automatically moving the catch 40 out of its path of movement against the tension of spring 42 which acts 25 to restore the catch to locking position. Such depression of the lever 28 also depresses a lever 43 pivoted at or adjacent its rear end to the rear wall of the cabinet and having a pin-and-slot connection at its forward end 30 with the lever 28. The lever 43 being in contact with the lever 37, further depresses the latter sufficiently to release the coin 36, which falls to the bottom of the cabinet. Also when the lever 28 is returned by said 35 spring S to normal position, it resets levers 43 and 37 for succeeding operations.

I claim:—

1. In a coin-controlled device of the character described, an actuating lever, a latch member normally disposed in the path of said lever to prevent actuation thereof, and mounted to rock on an axis parallel to said path, a coin chute, a second lever having one arm engaging said latch member and its other 55 arm engageable by a coin deposited in said chute to move the latch member out of the path of the first lever, and a third lever operable by the first lever to further move the second mentioned lever through operation of the actuating lever to release the coin, 60

2. In a coin-controlled device of the character described, an actuating bell-crank lever, a laterally displaceable latch member normally disposed in the path of said lever to prevent actuation thereof, a coin chute, a lever disposed at a right angle to said latch member having a portion disposed in the path of a coin deposited in said chute to initially move the latch member out of said path, and downwardly movable means to 70 further move the second mentioned lever through operation of the actuating lever so as to release the coin. 75

3. In a coin-controlled device of the character described, a cabinet having a coin chute, an actuating bell-crank lever pivoted within the cabinet, a displaceable latch member, means normally maintaining said latch member in the path of said lever to prevent actuation thereof, a lever pivoted within the cabinet disposed at a right angle to said latch member and having a portion disposed in the path of a coin deposited in said chute so that the coin will move the latch member out of said path, and a lever pivoted to the cabinet 80 and to the first mentioned lever engageable with the second mentioned lever to release the coin through operation of the actuating lever. 85

In testimony whereof I have hereunto set my hand.

ARTHUR WORRELL.
